CARL A. RICHTER, OF PFORZHEIM, GERMANY, ASSIGNOR TO THE FIRM OF FRIEDRICH SCHMOLCK, OF PFORZHEIM, GERMANY.

APPARATUS FOR PRODUCING WIRE-RING FABRIC.

1,100,098.

Specification of Letters Patent. Patented June 16, 1914.

Application filed August 4, 1911. Serial No. 642,328.

To all whom it may concern:

Be it known that I, CARL A. RICHTER, a subject of the German Emperor, residing at Pforzheim, Baden, in Germany, have invented certain new and useful Improvements in Apparatus for Producing Wire-Ring Fabric, of which the following is a specification.

The present invention has for its object certain improvements in apparatus for producing metal ring fabric.

According to the invention the top convolutions of a plurality of helically wound wires are simultaneously screwed into the fabric, so that each top convolution engages two adjacent rings previously produced, the advance of the helices being perpendicular to the row, whereupon the several convolutions are severed and the ends of the same united, this operation being repeated with the following convolutions after the fabric has been moved laterally. In the first instance each wire is wound around a rotatable spindle, and the coils are rotated so that the uppermost convolution of each wire helix becomes engaged with the fixed blade of a pair of shears, the rotation continuing until the end of the coil reaches a stop, when it is pressed by a spring onto the top of the fixed blade and held in this position until the other blade of the shears rises and severs the coil, whereupon the severed end of the convolution is forced up until both ends of the ring lie in the same plane. This new method lends itself to more rapid and better work than was possible with the previously known methods and apparatus.

Apparatus for carrying the improved method into effect is shown in the annexed drawings, with reference to which the invention will now be described.

Figure 1 is a front elevation of part of the machine; Fig. 1^a a detail thereof in section perpendicular to Fig. 1; Fig. 2 a vertical transverse section of Fig. 1; Fig. 2^a a section similar to Fig. 2, but to a larger scale; Fig. 2^b a plan view of certain of the parts shown in Fig. 2^a. Fig. 2^c a side view of a detail of the apparatus, partly in section; Fig. 2^d a plan view of Fig. 2^c. Fig. 3 a section of Fig. 1 on the line 1—2; Fig. 4 a plan of Fig. 2, some parts being omitted for the sake of clearness; Fig. 5 is a view drawn to a larger scale for

illustrating the addition of the links; Fig. 6 is a view of a movable frame carrying the ring fabric; Fig. 7 is a side view of part of the cutter; Fig. 7^a is an end elevation of one of the cutters, and Fig. 7^b a plan of Fig. 7; Fig. 8 is a view of the wire coiling apparatus, drawn to a larger scale; Fig. 8^a is an elevation of part of the mechanism for feeding the coils, and Fig. 8^b is a plan view thereof; Figs. 9 and 10 are diagrammatical views, showing two different arrangements of the wire coiling spindles; Figs. 11 and 12 show details of the cutter actuating mechanism.

The apparatus illustrated comprises a series of spindles 2 (of which there may be any desired number) on which the wires 1 are wound to form the helices 3. Each of the spindles is actuated by a short shaft, which carries a toothed wheel 14 (Fig. 8) and the end 14^a of which is screwed into a correspondingly tapped plate 15 so that the toothed wheel is raised or lowered when rotated, the other end of the shaft being bored axially to receive the spindle 2 and being carried loosely in another horizontal plate 16 to the upper face of which is fixed a third plate 17, the latter having a bore 17^a of suitable diameter to enable the said vertically disposed spindle 2 with wire thereon to rotate freely, the wire being fed to the spindle at right angles to the latter through a bore 18 provided in the plate 17. The upper ends of the spindles lie in holes 21^a in a plate 21. If the spindles are arranged in a circle the several toothed wheels 14 are meshed with a larger toothed wheel 22 which, when rotated by a shaft 19, drives the smaller wheels and in so doing causes the spindles 2 to rise by reason of the screwed ends 14^a turning in their tapped sockets. The wire coiled around each spindle 2 is in this case held firmly thereon by a friction wheel 20, which has a soft rubber face 20^a. The friction wheel 20 is fixed to the shaft 19, which has at its lower end a ratchet wheel 19^a (Figs. 8^a and 8^b) engaged with a pawl 19^b held against the wheel by a spring 19^c, so that rotation of the shaft in one direction is prevented by the said pawl. The wheel 22 is loose on the shaft 19, and is actuated by a reciprocating rack 22^a, whereby the spindles are alternately raised and lowered. During the ascending movement of the spindles the wheel 20 and shaft 19 are ro-

tated by friction with the wire being coiled on the spindles, but during the descent of the spindles the wheel 20 cannot rotate in the opposite direction, and its rubber face thus retains the wire coil formed in its raised position. The wire is thus drawn in and coiled around the spindles when the latter rise, but is held stationary as the spindles descend to their original positions. If the spindles are arranged in a straight row, the rotation thereof may be effected as shown in Fig. 9 by means of two parallel bars 100, 101 provided with racks engaged with an actuating pinion 102 by means of which they are reciprocated in opposite directions. The bars 100, 101 are provided with rubber facings which bear against the coils on the spindles with sufficient friction to rotate the coils while the spindles rise. While the spindles descend the coils are held at the top, as will be described hereinafter, and the friction of the rubber facings is not sufficient to pull the coils down while the spindles descend.

The wire helix 3 fed upward by the spindle 2 enters a semicircular recess 4 (Figs. 7, 7^a, 7^b) in a plate 5 forming one blade of a pair of shears, whence it coils up around the edge of the plate onto an inclined surface 6 on said plate, the slope of which surface corresponds with that of the wire; the helix then passes through a wedge shaped groove 7¹ at the upper end of the said inclined surface on the blade, and leaving this groove passes after a further quarter turn through a ring of the previously manufactured ring fabric 30 (Fig. 2^a) and after another half turn through the next adjacent ring and then finally after completing the last quarter of a turn passes onto a projection 7 over the said groove 7¹ and butts with its ends *i* (Figs. 2, 2^a, 2^c) against a stop 8¹ which projects toward the vertically depending manufactured fabric, said stop being formed on a vertical slide plate 8. The wire helix then remains stationary and is held fast by a slide 9 which descends and by means of depending springs 10 thereon holds the first convolution *i* firmly on the projection 7. Thereupon, a movable blade 11, sliding vertically at the side of the fixed blade 5, severs the first wire convolution at the narrower end of the wedge shaped groove 7¹ in the fixed blade; the plate 8 then rises and the further upward movement of the sliding blade pushes the severed end *i* (Fig. 2^b) of the convolution up until it registers with the other end of the convolution. The latter is thus flattened out, to form a complete ring in position in the fabric. The sliding blade and the slide 9 return to their original positions and release the links. The mechanism for actuating the blade 11 is shown in Figs. 11 and 12. The blade has lateral projections 11^a whereby it is engaged

with slotted arms of double armed levers 35, the other arms of which are connected by links 34 to levers 32 pivoted at 33. The levers 32 are depressed, for raising the blade, by cams 30 on a shaft 31. The blade 70 descends by gravity.

In fitting the rings in position as hereinbefore described, at the commencement of the operations, the intermediate rings *a*³, *a*⁷, *a*¹¹, in the series *a*¹, *a*³, *a*⁵, *a*⁷, *a*⁹, *a*¹¹, *a*¹³, 75 (Fig. 6) are omitted, and then the frame carrying the fabric is moved laterally to the extent of one ring-diameter so that the gaps are placed immediately above the wire helices, whereupon during the next operation of the apparatus the missing links are inserted in this row.

The object of forming the row of rings in two operations as described, that is to say, of forming alternate rings at each operation, 85 is to avoid excessive closeness of the spindles and the parts coacting therewith. If the number of rings is uneven, as in the example illustrated, one ring will be wasted at each second operation.

After formation of the row of rings as described, the vertically depending fabric supported by the frame 12 is raised so that the said row of rings is correctly positioned for the succeeding row *a*², *a*⁴, *a*⁶, *a*⁸, *a*¹⁰, *a*¹², 95 *a*¹⁴, to be fitted.

In the following row the new links will be displaced with respect to the previous row to the extent of half the diameter of the rings, so that the centers of new links lie 100 intermediate of the previously fitted links. For this purpose the frame 12 carrying the fabric is shifted laterally to the extent of half a ring-diameter for adding the rings *a*², *a*⁶, *a*¹⁰, *a*¹⁴, and is then moved in the opposite direction to the extent of one ring-diameter for adding rings *a*⁴, *a*⁸, *a*¹², in the gaps.

The shear blades are arranged in a straight line or in a circle according to the 110 formation to be given to the fabric. The fixed shear blades, having the semicircular recesses as described, also serve as guides for the helices and for this reason are cut away at the opposite side to the recess and 115 are curved at the beginning of the set-back as at 5¹, so that when the fixed blades are placed in their correct position side by side the said curve forms a quadrant with, and of the same radius as, the semicircular recess 4 in the base of the adjacent blade.

What I claim as my invention and desire to secure by Letters Patent of the United States is:—

In apparatus for producing fabric composed of interlinked wire rings, the combination of a fabric supporting frame, means for collectively feeding parallel coils of wire toward said frame and rotating such coils about their axes, said axes being substan- 125

130

tially parallel with the plane of the fabric supported by said frame, guides disposed to engage the forward ends of rotating wire coils fed toward the frame and to guide the 5 foremost convolution of each such coil through two rings of the fabric supported by said frame, said guides having sharp edges, and movable knives adapted to coact with said sharp edges for cutting off the 10 said foremost convolutions after their en-

gagement with the fabric and to flatten the convolutions which they have severed.

In witness whereof I have signed this specification in the presence of two witnesses.

CARL A. RICHTER.
